UNITED STATES PATENT OFFICE

95,827

DESIGN FOR A WRAP

Charles Hoffman, New York, N. Y.

Application April 24, 1935, Serial No. 56,534

Term of patent 3½ years

To all whom it may concern:

Be it known that I, Charles Hoffman, a citizen of the United States of America, residing in Manhattan, county of New York, and State of New York, have invented a new, original, and ornamental Design for a Wrap, of which the following is a specification, reference being had to the accompanying drawing, forming part thereof, wherein,

The lines radiating from the inner edges of the sleeves represent inverted tucks.

I claim:

The ornamental design for a wrap, substantially as shown and described.

CHARLES HOFFMAN.
